UNITED STATES PATENT OFFICE.

EDWARD GUY GOBEN, OF NEW ORLEANS, LOUISIANA, ASSIGNOR TO THE E. V. BENJAMIN COMPANY, INC., OF NEW ORLEANS, LOUISIANA, A CORPORATION OF LOUISIANA.

FOLDING MACHINE.

Application filed December 8, 1919. Serial No. 343,390.

To all whom it may concern:

Be it known that I, EDWARD GUY GOBEN, citizen of the United States, and resident of New Orleans, in the parish of Orleans and State of Louisiana, have invented certain new and useful Improvements in a Folding Machine, of which the following is a specification.

This invention relates to a folding machine. Its object is the production of a machine which will remove pieces of cloth or other material from the cylinder of a printing press and fold all of them in a similar manner. The folding machine is adapted to operate with the cutting machine described in application, Serial Number 343,391, filed Dec. 8, 1919.

The said cutting machine cuts cloth or other material in equal lengths, for delivery to a printing press, while the present invention removes the cloth or other material from the printing press and delivers it folded for further operations.

The folding machine comprises essentially a receiving drum comprising a plurality of receiving wheels secured to a rotary shaft. All of the wheels except one have connected thereto automatically operated grippers, to grip the material operated upon and draw it from the cylinder of the printing press with which it coacts. One of the wheels of the receiving drum coacts with a releasing device for the grippers. The folding machine also contains a discharging drum, comprising a plurality of discharging wheels carried on a rotating shaft. The latter wheels carry a pinching bar having fingers, by means of which the pieces of material operated upon are drawn from the receiving wheels. By means of a releasing mechanism the fingers of the pinching bar releases the material and it is discharged from the machine in equal folded portions. The pinching bar with its appurtenances operates automatically and its operations are timed to draw the pieces of material from the receiving wheels immediately after the grippers of the latter are released.

In the accompanying drawings, Fig. 1 is a top plan view of one form of the improved folding machine with a fragmentary portion of a printing press, Fig. 2 shows a section of Fig. 1 on the line 2, 2 and a fragmentary portion of a cutting machine, Fig. 3 represents an enlarged section of Fig. 1

on the line 3, 3 with a portion of the folding machine shown in dotted lines and Fig. 4 is a section of Fig. 1 on the lines 4, 4.

The folding machine is indicated with a fragmentary portion of a printing press having the side frames 15 and 16 in which is journaled the shaft 17. A driving pulley 18 and printing cylinder 19 are fastened to the shaft 17. The cylinder is provided with the usual grippers as 20. The supporting beams as 21 of a cutting machine are supported on the side frames 15 and 16. With the frames 15 and 16 are formed the accompanying pairs of journal bearings 26, 27 and 28, 29. A shaft 30 is journaled in the bearings 26, 27 and on which is fastened a receiving drum R. The drum comprises a plurality of receiving wheels 31 and 31^a. Each of the wheels comprises the rim 32 with the spokes 33. A lug 34 extends from the wheel 31^a. A circular annular web 35 with the circular annular slot 36 is formed with the wheels 31 and 31^a. A gear 37 is fastened to the shaft 30 adjacent to one end thereof and bolts 38, 39 connect the gear 37 with all the wheels 31 and 31^a. In the rim 32 of each of the wheels 31, 31^a is seated the finger bar 40 having formed therewith and extending from its outer face the receiving and stationary gripping fingers 41. Screws 42 fasten the bar 40 to the rims 32 of the said wheels. Supports 43, 44 and 45 are fastened to the shaft 30 by means of screws 46. Each of the supports comprises the body portion 47, having the hub 48 at one end, the curved projection 49 at the other end and the hub 50 adjacent to the projection 49. A hub 51 is formed with the portion 47 of the supports 43 and 44. A buffer support 52 is carried on each of the projections 50 and is held in place by means of a screw 53 and dowel pin 54. A buffer 55, preferably of leather, is fastened in a dovetailed opening in the buffer support 52.

A bolt 56 extends through each of the slots 36 of the wheels 31 and 31^a and through the hubs 51 of the body portion 47. Nuts 58 at the ends of the bolt 56 hold it in place. On the said bolt 56 are secured the grippers 60 by means of the screws 61.

A stationary cam 62 with the guide finger 63, the cam surface 64 and the vertical leg 64^a has formed therewith the bracket 65. The latter is fastened to the frame 16,

by means of the bolt 66. The shaft 30 extends through the cam 62 at the upper portion thereof.

To and in front of the support 45 is pivoted on the bolt 56, the lever having the arms 67 and 68. A cam roller 70 is journaled on a pin 71 extending from the arm 67, which roller is adapted to ride on the cam surface 64. At the end of the arm 10 68 is secured a pivot 72 on which is pivoted a head 73 of the stem 74. The outer end of the stem 74 extends through the opening in the lug 34 of the wheel 31^a. A spring 75 encircles the stem 74 and bears between 15 the head 73 and the lug 34.

A shaft 80 journalled in the journal bearings 28, 29 has fastened thereto the discharging drum D, comprising the discharging wheels 81. Each of the wheels 81 comprises 20 the rim 82 having the opening 83 and the spokes 84. A gear 85 with the lug 86 is fastened to the shaft 80, and bolts 87, 88 connect the spur gear 85 and all the wheels 81. A cam is indicated at 89 which has 25 formed therewith the cam surface 90 and the bracket 91. Bolts 92 secure the bracket 91 to the frame 15. A pinching bar 93 having the fingers 94 and recesses 95, is fastened to each arm 96. The latter are fastened to the 30 bolt 87.

In the opening 83 are fastened, to one of the spokes 84 of each of the wheels 81, the presser plate 98 and the supporting plate 99. The plate 98 is preferably made of softer 35 material than the plate 99. The plates are fastened to each other and to the said spokes 84 by the screws 100. A lever having the arms 101 and 102 is fastened to the bolt 87. A roller 103 is journalled on a pin 104 extending from the arm 101, and which is 40 adapted to ride on the cam surface 90. The arm 102 has formed therewith a cavity 105 in which extends a pin 106. A head 107 of a stem 108 is located in the cavity 105. 45 The outer end of the stem 108 extends through the lug 86 of the spur gear 85. A thread 109 is cut on the stem 108 at the inner portion thereof for an adjusting nut 110. A spring 112 encircles the stem 108 and 50 bears between the lug 86 and the adjusting nut 110. A gear 115 on the shaft 17 of the press cylinder 19 meshes with a gear 116 fastened to the shaft 30. The stem 74 can be threaded for an adjusting nut similar to 55 the nut 110.

A prism landing block 120 with the apex 121 and preferably of wood has connected thereto the side plates 122, which are fastened to the side frames 15 and 16.

60 To operate the folding machine the pulley 18 is turned by means of a belt, not shown, and the spur gear 115 and cylinder 19 are caused to rotate in the direction of the arrow A.

65 The gear 115 rotates the spur gear 116,

causing the shaft 30 with the spur gear 37 to rotate, whereby the receiving drum R is caused to rotate in the direction of the arrow B. The spur gear 37 rotates the spur gear 85, causing the discharging drum D to 70 rotate in the direction of the arrow C.

The cut pieces of material to be folded are delivered from the cutting machine referred to, by means of appurtenances not shown located between the supporting beams 21, to 75 the printing press cylinder 19. The latter, by means of its grippers 20 carries the material on the surface thereof in proper position for the appurtenances of the folding machine.

The grippers 60 of the receiving drum R grip the cut pieces of material immediately after it is released by the grippers 20, and carries them on the rims 32 of the receiving wheels 31 and 31^a. The gripper 60 of each 80 wheel 31 can be located in proper position to suit different lengths of cloth or other material 120, by loosening the screws 46, excepting the one for the support 45 and swinging the drum R until the circumferential distance between the fingers 41 and the buffer 55 equals one-half of the length of the pieces of material to be folded after which the said screws are again tightened in place. When the roller 70 rides on the cam 95 surface 64 of the stationary cam 62 the grippers 60 are open, and they will close as soon as the roller 70 reaches the vertical leg 64^a, by virtue of the tension of the spring 75 which forces down the stem 74. Just before the grippers 60 close the pieces of cloth on the drum 19 are in proper position to be engaged by them. The pieces of material are now carried on the drum R being located on the rims 32. The fingers 41 will engage 100 the middle portions of the pieces 120 and carry them until they are opposite the spaces 83, which occurs when a plane passing through the longitudinal axis of the shafts 30 and 80 is reached. At this instant the 105 roller 103 starts to ride on the stationary cam surface 90, and thereby the pinching bar 93 is swung to its closed position. At the same time the fingers 41 move into the recesses 95 and the fingers 94 grip the pieces 110 of material 120. The material is now drawn to the rims 82 of the wheels 81, in a folded position with a crease formed on the line across the piece of material where it was in contact with the receiving and gripping fingers 41. When the roller 103 leaves the cam surface 90, the pieces of material are 115 released by means of the tension of the spring 112, which moves the arms 96 and thereby releases the material from the fingers 94 and the presser plate 98. The folded material or pieces of cut cloth are deposited on the landing block 120, the crease of the fold located at the apex 121 of said block.

Having described my invention what 120

I desire to secure by Letters Patent and claim is:

1. In a folding machine the combination of a rotating receiving drum for pieces of material, a rotating discharging drum with its periphery adjacent to the periphery of the receiving drum, stationary receiving gripping fingers extending from the periphery of the receiving drum, automatically operated grippers on the receiving drum spaced a predetermined circumferential distance from the receiving gripping fingers, a presser plate fastened to the discharging drum in an opening extending through the rim thereof and an automatically operated pinching bar having fingers and recesses between its fingers located within said opening coacting with said presser plate and said receiving gripping fingers, the rotations of the drums timed so that the receiving, gripping fingers of the receiving drum will deliver the pieces of material in a folded position between said bar and presser plate, the receiving fingers locating themselves in the recesses of the pinching bar when the latter is closed with said presser plate and a landing block adjacent to the discharging drum.
2. In a folding machine the combination of a receiving drum for pieces of material, a rotating discharging drum with its periphery adjacent to the periphery of the receiving drum, the rotations of the drums timed to enable the drums to coact with each other, a plurality of receiving wheels constituting the receiving drum, a finger bar connecting
- the rims of said receiving wheels, stationary gripping receiving fingers extending from the outer face of said bar, a circular annular web having a circular annular slot formed with each receiving wheel, a support adjustably connected to one of said receiving wheels, a lever with a pair of arms for one of said receiving wheels pivoted to a bolt extending through said support and said wheel, a roller pivoted to one of said arms, a stem with its head pivoted to the other arm, the other end of the stem extending through an opening in a lug formed with said one wheel, a spring bearing between said lug and head, a stationary cam in the machine to contact with said roller, similar supports adjustably connected to all the other wheels, the said bolt extending through the latter supports, a gripper for each of the latter wheels attached to said bolt, a buffer for the gripper on each of the latter supports, each of said supports spaced a predetermined circumferential distance from the receiving fingers, automatically actuated pinching means on the discharging drum to pinch said pieces of material at the portions engaged by the receiving fingers and thereby pull said pieces of material in a folded position from said receiving drum and a landing block adjacent to the discharging drum.

Signed at New Orleans, in the parish of Orleans and State of Louisiana, this first day of December A. D. 1919.

EDWARD GUY GOBEN.
